GAUGING TOOL

Henry H. Talboys, Milwaukee, Wis., assignor to
Nordberg Manufacturing Company, Milwaukee,
Wis., a corporation of Wisconsin

Application April 15, 1946, Serial No. 662,175

14 Claims. (Cl. 254—43)

1 My invention relates to an improvement in track or rail gauges and has for one purpose to provide a track gauge effective for use in connection with laying rails, such as the rails of railroad tracks.

Another purpose is to provide a gauging tool which may be applied to a fixed rail of a track and may be employed to move the other loose rail toward or away from the fixed rail, prior to the securing of the loose rail to the ties.

Another purpose is to provide a rail gauge which can be employed to shift a loose rail to the proper distance from a fixed rail, without tilting the loose rail from its desired position.

Another purpose is to provide a gauge which is effective to gauge a rail, whether the rail is set wider or narrower than the desired gauge.

Another purpose is to provide a simple, compact and light track gauge structure.

Another purpose is to provide indicating means to indicate when the gauge is properly engaged with the rail.

Other purposes will appear from time to time in the course of the specification and claims.

I illustrate the invention more or less diagrammatically in the accompanying drawings wherein:

Figure 1 is a section taken in a plane perpendicular to the long extension of the rails;

Figure 2 is a similar section, with a portion omitted, illustrating the parts in a different position;

Figure 3 is a section on the line 3—3 of Figure 1;

Figure 4 is a section on the line 4—4 of Figure 1;

Figure 5 is an enlarged section on the line 5—5 of Figure 4;

Figure 6 is a section on the line 6—6 of Figure 1; and

Figure 7 is a section on the line 7—7 of Figure 1.

Like parts are indicated by like symbols throughout the specification and drawings.

Referring to the drawings, 1 generally indicates a railroad tie upon which rests the bottom flange 3 of the fixed rail 2, to which the gauging tool may be secured, in order to gauge or move the opposite rail into proper relation with the rail 2; 4 indicates the top flange commonly called the head or ball of the rail 2. The opposite rail 2a is indicated with its bottom flange 3a and its head 4a. I illustrate any suitable gauge body member which spans the rails. It may include for example side webs or walls 5, 6, which may be

lightened by apertures 5a, 6a and are shown with overlapping top and bottom flanges secured, for example, by metallic cement. 7 indicates the top wall component of the thus formed gauging body or frame and 8 the bottom component. It will be noticed that the top component is broken away at 1a and 1b, for purposes which will later appear, and the bottom component is broken away at 8a for a purpose which will later appear.

10 11 indicates fixed bracket members extending downwardly from angle members or supports 11a on walls 5 and 6 of the body member, each having an outwardly generally upright gauging face 12 which may be opposed to the inner face of the head 4 of the rail 2. 9 is a movable abutment having an adjustable element 10 adapted to engage the opposite or outer face of the head 4 of the rail 2, the member 9 being unitary with the lever 23 which is pivoted as at 24 to the gauge body.

ing member is pivoted as at 32, to the gauging body, the pivot being adjacent the lower face of the body. Secured to the side members 5, 6 of the gauging body are blocks 33 adapted to engage the top head 4a of the said rail 2a.

In order to limit or fix the distance between the two rails I provide a movable gauging abutment member 34, in the form of a fork adapted to engage the inner face of the head 4a of the loose rail 2a. It is screw threaded or otherwise adjustably mounted upon a stem 35. The forward gauging tips or ends 36 are downwardly bent so that they can extend downwardly through the aperture 8a in proper rail engaging position when their intermediate portion 37 is resting upon the bottom wall of the gauging body, in the position shown in Figure 1. The stem 35 is pivoted as at 38 to an adjusting arm 39. The coil spring 40 extends between an abutment aperture 41 in the lower wall of the gauging body, and an end of the stem 35. It is adapted normally to urge the lever 39 about its axis 42. The lever 39 carries a top plate 43 having an adjusting pin 44 which may be opposed to the adjusting cam 45, pivoted as at 46 between the exterior reinforcements 47. It will be noted that the lever 39 includes two components which extend about the cam 45, on opposite sides thereof, as shown in Figure 4. The cam 45 is provided with a camming face 50 in which are formed a plurality of adjusting apertures 51 adapted selectively to receive the pin 44.

The user can gauge the effective distance between the tips 36 of the gauge member 34 and the face 12 of the fixed abutment 11 by withdrawing the plate 43 slightly and rotating the cam 45 to oppose the desired aperture 51 to the pin 44. The spring 40 is effective to rotate the lever assembly 39 counterclockwise about its axis 42, thereby holding the pin 44 engaged in its appropriate aperture 51, and maintaining the plate 43 in gauging relationship with the opposed face of the cam. Thus as the cam 45 is rotated in one direction, it decreases the distance between the surfaces 12 and 36. When rotated in the opposite direction it increases said distance.

Note also that pivoted to the member 37 are indicating pins 60 each having a head or top portion 61 which may be colored red, extending upwardly through the apertures 62 in the upper wall of the gauging body. When the member 34 has dropped to the proper position, in which it is shown in Figure 1, the heads 61 are in lowered position, as shown in Figure 1. But if the portions 36 ride on the top of the rail, as shown in Figure 2, then the heads 61 are fully exposed, and warn the user that the rails 2 and 2a are not in proper position.

Any suitable carrying handle or handles 70 may be employed, for example in raising and lowering the gauge.

It will be realized that, whereas, I have described and illustrated a practical and operative device, nevertheless many changes may be made in the size, shape, number and disposition of parts without departing from the spirit of my invention. I therefore wish my description and drawings to be taken as in a broad sense illustrative or diagrammatic, rather than as limiting me to my precise showing.

The use and operation of the invention are as follows:

Assume that the rail 2 is already secured to the ties of a track, and that the loose rail 2a is

in approximately correct position. The user spans the two rails with the gauging body, positioning the head 4 of the fixed rail between the abutments 10, and 11, dropping the hooks 30 and 31 about the opposite sides of the loose rail 2a. If the loose rail is outwardly out of place in relation to the fixed rail 2, the user moves the handle 15 to the right, referring to the position of the parts as shown in Figure 1, and thereby urges the abutment 10 to the left against the rail head 4. The result is to bring the abutment face 12 of the member 11 snugly against the inner face of the fixed rail head 4. A continued movement of the lever 15 to the right will have no further effect on the positioning of the link 21, and the pivot pin 17 is held against further rightward movement in the slot 18. Thereafter, the lower end of the lever 15, moving to the left rotates counterclockwise about the pivot 32 and thrusts the hook point 30a against the web of the rail 2a, urging it to the right against the abutment 36. When this movement is completed the two rails are properly gauged apart, the loose rail being held against the abutment 36, and the abutment 11 spacing the loose rail 2a in relation to the fixed rail 2. It will be noted that since the thrust of the hook portion 30a is intermediate between the top and the bottom of the rail there is no tendency to tilt the rail or to disturb the normal or desired plane of the lower face of the flange 3a.

If the loose rail is somewhat too close to the fixed rail when the gauging body is laid on the two rails, the abutment 36 is free to pivot upwardly about its axis 38, as is indicated in Figure 2, and will rest on the upper surface of the top rail head 4a. A rotation of the lever 15 in a counterclockwise direction will cause the opposite hook point 31a to thrust outwardly against the web of the loose rail. As the rail is urged to the left, referring to the position of the parts in Figure 1, the raised abutment 36 will override the rail until it is free to drop into the position in which it is shown in Figure 1. The indicator 61 indicates when this has taken place. Thereafter the direction of rotation of the lever 15 may be reversed, and the loose rail urged against the abutment 36, the final gauging being between the abutting surfaces 12 and 36. The cam 45 may be adjusted to vary the spacing between rails, as may be necessary when laying rails about curves.

I claim:

1. In a track gauge, a gauge body adapted to span the rails of a track, an abutment fixed in relation to said body, adapted to be opposed to an inner face of a rail fixed on the track, a gauge member, movably located on said body, and including an end portion adapted to engage the inner face of a loose rail, means for initially urging said fixed abutment against the inner face of the fixed rail and means for thereafter urging a loose rail against said gauge member.

2. In a track gauge, a gauge body adapted to span the rails of a track, an abutment fixed in relation to said body, adapted to be opposed to an inner face of a rail fixed on the track, a gauge member, movably located on said body, and including an end portion adapted to engage the inner face of a loose rail, and unitary means for initially urging said fixed abutment against the inner face of the fixed rail and for thereafter urging a loose rail against said gauge member.

3. In a track gauge, a gauge body adapted to span the rails of a track, an abutment fixed in

relation to said body, adapted to be opposed to an inner face of a rail fixed on the track, a gauge member, movably located on said body, and including an end portion adapted to engage the inner face of a loose rail, and unitary means for initially urging said fixed abutment against the inner face of the fixed rail and for thereafter urging said loose rail against said gauge member, including a single, manually operable floating lever supported on said gauge body, a lever pivoted at each end of said body including parts exterior to each rail, and link connections between each said last mentioned lever and said floating lever.

4. In a track gauge, a gauge body adapted to span the rails of a track, an abutment fixed in relation to said body, adapted to be opposed to an inner face of a rail fixed on the track, a gauge member, movably located on said body, and including an end portion adapted to engage the inner face of a loose rail, and unitary means for initially urging said fixed abutment against the inner face of the fixed rail and for thereafter urging a loose rail against said gauge member, including a single, manually operable floating lever supported on said gauge body, a lever movable on one end of said gauge body, to move the body in a direction to move said fixed abutment against the fixed rail, a lever movable on the opposite side of said gauge body adapted to move said loose rail toward said movable gauge member, and actuating connections between both said members and said lever.

5. In a track gauge, a body adapted to span the rails of a track, an abutment, normally fixed in relation to said body, adapted to be opposed to an inner face of a rail fixed on said track, a lever on said body, adapted to be thrust against an outer face of said fixed rail, thereby to urge said fixed abutment against the said inner face of said fixed rail, a gauging member positioned adjacent the opposite end of said body element and adapted to engage an inner face of a loose rail on said track, and a lever movably mounted on said body, adapted to move said loose rail against said gauging member.

6. In a track gauge, a gauge body adapted to span the rails of a track, an abutment fixed in relation to said body, adapted to be opposed to an inner face of a rail fixed on the track, a movable element on said body, including an end portion adapted to engage the inner face of a loose rail, a lever for initially moving said gauge body to urge said fixed abutment against the inner face of the fixed rail, a second lever adapted thereafter to urge a loose rail against said movable element, and indicating means responsive to changes in position of said movable element, adapted to indicate the location of said movable element.

7. In a track gauge, a gauge body adapted to span the rails of a track, an abutment fixed in relation to said body, adapted to be opposed to an inner face of a rail fixed on the track, a gauge element, movably located on said body, and including an end portion adapted to engage the inner face of a loose rail, means for initially urging said fixed abutment against the inner face of the fixed rail, means for thereafter urging a loose rail against said gauge element, and means for adjusting the effective gauging position of said gauge element.

8. In a track gauge, a gauge body adapted to span the rails of a track, an abutment, fixed in relation to said body, adapted to be opposed to

an inner face of a rail fixed on the track, a movably mounted gauge element adapted to engage the inner face of an opposite rail, means for urging said fixed abutment against the inner face of the fixed rail and for urging the inner face of the loose rail against said gauge element.

9. In a track gauge, a gauge body adapted to span the rails of a track, an abutment, fixed in relation to said body, adapted to be opposed to an inner face of a rail fixed on the track, a movably mounted gauge element adapted to engage the inner face of an opposite rail, means for urging said fixed abutment against the inner face of the fixed rail and for urging the inner face of the loose rail against said gauge element, including a handle movable on said gauge body, a member movable on said gauge body, adapted to engage an outer face of said fixed rail, an actuating connection between said member and said handle adapted, in response to said movement of said handle, to draw said fixed abutment against the inner face of the fixed rail, an actuating fork having tines adapted to be positioned at opposite sides of said loose rail, and an actuating connection between said fork and said handle.

10. In a track gauge, a transversely slidable gauge body adapted to span the rails of a track, a fixed abutment for fixing said gauge body in relation to a rail fixed on the track, adapted to engage the inner face of said fixed rail, and means for gauging a loose rail in relation to said fixed rail, including a gauge abutment, movable on said gauge body, and adapted to engage an inner face of the loose rail, and a lever adapted to move said loose rail thereagainst.

11. In a track gauge, a gauge body adapted to span the rails of a track, means for fixing said gauge body in relation to a rail fixed on the track, and means for gauging a loose rail in relation to said fixed rail, including a positioning abutment, movable on said gauge body, and adapted to engage an inner face of the loose rail, and means for moving said loose rail thereagainst, including a fork having tines adapted to engage opposite sides of said loose rail, and means for moving said fork to push the loose rail either toward or from the fixed rail, said positioning abutment being adapted to ride on the top of said loose rail, when said loose rail is initially too close to said fixed rail, and signal means adapted to indicate when said positioning abutment is in raised position on said loose rail.

12. In a track gauge, a gauge body adapted to span the rails of a track, means for fixing said gauge body in relation to a rail fixed on the track, and means for gauging a loose rail in relation to said fixed rail, including a positioning abutment, movable on said gauge body, and adapted to engage an inner face of the loose rail, and means for moving said loose rail thereagainst, including a fork having tines adapted to engage opposite sides of said loose rail, and means for moving said fork to push the loose rail either toward or from the fixed rail, said positioning abutment being adapted to ride on the top of said loose rail, when said loose rail is initially too close to said fixed rail, and means for adjusting said positioning abutment.

13. In a track gauge, a gauge body adapted to span the rails of a track, means for fixing said gauge body in relation to a rail fixed on the track, and means for gauging a loose rail in relation to said fixed rail, including a positioning abutment, movable on said gauge body, and

adapted to engage an inner face of the loose rail, and means for moving said loose rail thereagainst, including a fork having tines adapted to engage opposite sides of said loose rail, and means for moving said fork to push the loose rail either toward or from the fixed rail, said positioning abutment being adapted to ride on the top of said loose rail, when said loose rail is initially too close to said fixed rail, and means for adjusting said positioning abutment, including a lever secured to one end of said abutment, an adjusting cam engageable with the other end of the lever, and yielding means adapted normally to urge said lever against said cam.

14. In a track gauge, a gauge body adapted to span the rails of a track, means for fixing said gauge body in relation to a rail fixed on the track, and means for gauging a loose rail in relation to said fixed rail, including a positioning abutment, movable on said gauge body, and adapted to engage an inner face of the loose rail, and means for moving said loose rail thereagainst, including a fork having tines adapted to engage opposite sides of said loose rail, and means for

5

10

20

moving said fork to push the loose rail either toward or from the fixed rail, said positioning abutment being adapted to ride on the top of said loose rail, when said loose rail is initially too close to said fixed rail, and means for adjusting said positioning abutment, including a lever secured to one end of said abutment, an adjusting cam engageable with the other end of the lever, and yielding means adapted normally to urge said lever against said cam, said lever having a positioning pin opposed to said cam, said cam having a plurality of apertures adapted respectively to receive said pin at various positions of the lever.
